[57] CLAIM

The ornamental design for a 35 mm camera, as shown and described.

DESCRIPTION

FIG. 1 is a front, top and right side perspective view of a 35 mm camera showing my new design;

FIG. 2 is a front elevational view thereof;

FIG. 3 is a top plan view thereof;

FIG. 4 is a left side elevational view thereof;

FIG. 5 is a right side elevational view thereof;

FIG. 6 is a bottom plan view thereof;

FIG. 7 is a rear elevational view thereof;

FIG. 8 is a front, top and right side perspective view thereof with a removable remote controller detached therefrom;

FIG. 9 is a top plan view of a second modified embodiment of the camera disclosed in FIGS. 1-8;

FIG. 10 is a left side elevational view thereof;

FIG. 11 is a right side elevational view thereof;

FIG. 12 is a bottom plan view thereof; and,

FIG. 13 is a rear elevational view thereof.

The front of the second embodiment of the 35 mm camera is identical to that of FIGS. 1,2 and 8 of the first embodiment.
